UNITED STATES PATENT OFFICE.

ARTHUR W. WELLS, OF BOSTON, MASSACHUSETTS, ASSIGNOR OF ONE-HALF
TO JANE E. BISHOP, OF SAME PLACE.

TRAMWAY-SWITCH.

SPECIFICATION forming part of Letters Patent No. 608,090, dated July 26, 1898.

Application filed January 27, 1898. Serial No. 668,194. (No model.)

To all whom it may concern:

Be it known that I, ARTHUR W. WELLS, a citizen of the United States, residing at Boston, in the county of Suffolk and State of Massachusetts, have invented certain new and useful Improvements in Tramway-Switches; and I do hereby declare the following to be a full, clear, and exact description of the invention, such as will enable others skilled in the art to which it appertains to make and use the same.

This invention relates to tramway-switches; and it consists, essentially, of a switch-throw located between main-track rails and operatively connected to a switch-point at a distance therefrom, the said throw being located in a bed and adapted to be actuated by a shipping-wheel of a specific form of construction carried at the end of a tram-car and adjustable vertically through the medium of a lever carrying a roller which is permitted to have lateral adjustment to swing or shift the shipping-roller to one side or the other.

The invention further consists of electric heating devices, in connection with the throw-bed and the switch-point, to prevent a congegation of ice and snow in and around the working parts, and thereby do away with the use of salt or other thawing materials, as well as manual labor, to keep the said parts clear.

The invention further consists of the details of construction and arrangement of the several parts, which will be more fully hereinafter described and claimed.

The object of the invention is to produce a positively-acting switch for tramways that can be operated by relatively coacting mechanism on the end of a tram-car, without requiring other means of an extraneous or manual nature, to shift the throw and arrange a switch-point relatively to a main line and side track or curve.

In the accompanying drawings, Figure 1 is a perspective view of a portion of a tram-car and track - rails embodying the invention. Fig. 2 is an irregular section including the throw and switch-point and the mechanism connecting the same. Fig. 3 is a detail sectional view of a part of the throw-bed, showing the electric heaters therein. Fig. 4 is a sectional view of the operating mechanism connecting the throw and switch-point shafts.

Fig. 5 is a detail perspective view of the shipping-wheel and the parts carrying the same, together with the operating-lever therefor. 55

Referring to the drawings, wherein similar numerals of reference are employed to indicate corresponding parts in the several views, the numeral 1 designates main-track rails, and 2 side-track rails, the latter embodying 60 a movable switch-point 3, which leads into or coacts with the said main - track rail. Between the said main-track rails and at a suitable distance from the switch-point 3 a bed 4 is located and arranged in the form of a box 65 with an upper elongated substantially elliptical groove 5 therein, which has an entrance-groove 6 at one end and an exit-groove 7 at the opposite end. It will be understood, however, that the said entrance and exit 70 grooves may be arranged in reverse order and that the exit-groove might be used as the entrance-groove, and vice versa. Within the groove 5 is horizontally disposed and movably mounted a throw 8, which is of the 75 same shape as said groove, but of course much smaller, to accommodate or compensate for a lateral movement thereof. The said throw has opposite reduced ends 9 and at the center is provided with an annular bearing-plate or circle 10, which is preferably grooved to form a seat for antifrictional balls or analogous devices coacting with an adjacent surface. Depending from the center of the said throw is a square shaft 11, having keyed on the lower end thereof a segmental sprocket 12, and engaging the said sprocket is a section of a sprocket-belt 13.

At a suitable distance from the said shaft 11 and to one side of the main-track rails a second angular shaft 14 is situated, and on the upper end thereof the switch-point 3 is secured. On the lower end of the said shaft 14 a second segmental sprocket 15 is suitably secured and is of less dimension than the 95 sprocket 12. The sprocket 15 is also engaged by a sectional chain belt 16, and to the free ends of each of the sectional chain belts rods 17 are secured and have their inner ends screw-threaded and engaged by turnbuckles 18, by means of which the requisite tension on the said sectional belts is maintained. 100

The operation of the devices thus far described is very simple, and by pressing the

right end of the throw 8, as shown in the accompanying drawings, in the direction of the transversely-positioned arrow the shaft 11 will be rotated and its movement transmitted 5 through the sprocket 12, by means of the sectional chain belt, to the sprocket 15 and to the shaft 14, and consequently shift the switch-point 3 in the position shown in Fig. 1 and close the main line. The device for operating 10 the throw having passed around the same toward the exit-groove 7 will strike the opposite end of said throw and press said end toward the same side of the groove 5 adjacent to which the opposite end of said throw 15 has been located, thereby moving the shaft 11 in the opposite direction, and through the shaft 14 and the connections set forth between said shaft the switch-point 3 is shifted in the opposite direction, the main-track rails opened 20 and the side tracks let into the said main-track rail. Of course this is one mode of operation in view of the arrangement, and others may be arranged by changing the position of the parts, which might ensue without departing 25 from the nature or spirit of the invention.

The bed 4 is preferably arranged in box form, as previously set forth, to provide a chamber which may be continued under the switch-point or an independent chamber established 30 under said point and connected to the said box by means of suitable pipes. Furthermore, the said box can have other pipes secured thereto and extend to curves connecting with chambers or conduits located under the latter. This arrangement of parts is to prevent the congregation of ice and snow around the working parts of the switch and also in connection with curve-rails, and as a heating medium oppositely-positioned 35 electric heaters 19 are suitably located in said bed 4 and connected up to electric conductors running from a source of electrical generation. From this one center heat could be conducted in a number of different 40 directions, and as the means for doing this are well known in the art they have not been completely illustrated.

As a preferred means for operating the switch-throw 8 a shipping roller or wheel 20 is carried at one or both ends of the tram-car and directly under the end platforms thereof. This shipping roller or wheel is supported in a yoke 21, carried on the outer end of an arm 22, which is normally positioned obliquely 50 and has its rear end pivotally mounted under the bed of the car. In rear of the yoke 21 a guide 23 is mounted on said arm and confines between the same a grooved roller 24, rotatably mounted on a rod 25, carried by the opposite 55 ends of a yoke 26, located at the lower outwardly-extending ends 27 of an operating lever 28. The roller 24 is loose on the rod 25, so as to have lateral play, and surrounding the said rod and bearing against the opposite sides 60 of said roller are coiled springs 29, which tend to normally restore the said roller in central position on the said rod. The lever 28 is ful-

crumed on the end of the car, as at 30, and at its upper end is provided with a grip 31 and a spring-actuated slide-dog or analogous device 32, which engages a horizontally-disposed notched plate 33. The roller 24 in the adjustment of the arm 22 moves lengthwise of the guide 23, and when the lever 28 is pulled inwardly toward the end of the car the said arm 70 22 and the shipping roller or wheel 20 are raised a proper distance above the road-bed and high enough to prevent contact with any objects over which the car may pass under ordinary conditions. When the lever 28 is moved outwardly from the end of the car, the arm 22 and the shipping-wheel 20 are forced downwardly, the adjustment in this direction being sustained through the spring-actuated sliding dog on the lever engaging the notch-plate 33. In the use of this shipping-roller and the devices connected thereto with the throw heretofore set forth said roller is let down into the entrance-groove 6 when the car is moving in the direction of the elongated 80 arrow longitudinally disposed on the said throw, and the latter is forced over in the direction of the arrow heretofore referred to, and the said shipping-roller moves around the throw, being allowed lateral play through 90 the pivotal connection of the arm 22 with the car-body until it reaches the opposite end of said throw, which it moves in a similar direction and passes out through the exit-groove 7. The arm 22 is restored to its normal position 100 through the medium of the springs 29 by reason of the fact that the roller 24, which is held in the guide 23, will be forced back to a central position after the resistance is removed from the said shipping-roller. Of course the throw 8 can be operated from the end opposite to that set forth, as previously indicated, and said throw will be sufficiently long to permit the wheels of the tram-car to pass over the switch-point 3 before said throw 110 is again operated to open the said point.

The shipping-roller 20 can be mounted either at one side or the other of the platform or in the center thereof and might be equally well operated from one side and engage a throw outside of the main-track rail. The arm carrying the shipping-roller and the co-acting parts will not interfere with the application of a suitable fender. The bed 4 can also be secured to cross-ties or sleepers, if desired, and the upper surface roughened to prevent horses or pedestrians slipping thereon. Other changes within the scope of the invention can be made, and particularly in the details of minor importance, as well as the dimension and proportions, without sacrificing any of the advantages of the invention.

Having thus described the invention, what is claimed as new is—

1. In a switch of the character set forth, 130 the combination of a grooved bed, a throw mounted in said bed, a depending shaft connected to said throw, a switch-point located at a distance from the throw and also having

- a depending shaft, segmental sprockets on the said shafts, sectional chain belts engaging the said sprockets, means for adjusting said sectional chain belts, track-rails, and means for operating the said switch-throw, substantially as described.
2. In a switch of the character set forth, the combination of track-rails, a bed mounted between a part of said rails, an elongated longitudinally-arranged switch-throw movably located in said bed, a switch-point at a distance from said bed, depending angular shafts connected to the throw and switch-point, segmental sprockets on the said shafts, sectional chain belts engaging the said sprockets, rods attached to the ends of said sectional chain belts, turnbuckles adjustably connecting the said rods, and means for operating the throw, substantially as described.
3. In combination with a tram-car, of a laterally and vertically movable arm, a shipping-roller carried at the outer free end of said arm, a lever carrying a spring-actuated roller engaging said arm, and a throw adapted to be operated by the shipping-roller, substantially as described.
4. In combination with a tram-car, of a vertically and laterally adjustable arm con-
- nected thereto having a shipping roller or wheel in the outer free end thereof, a guide 30 mounted on the said arm, a lever pivoted to the end of the car having a lower angularly-extending end carrying a yoke in which a rod is supported, a roller movably mounted on the said rod and located in the said guide, 35 springs on the said rod bearing against opposite sides of said roller, means for sustaining the adjustment of the said lever, and a switch-throw adapted to be engaged by the said shipping-roller, substantially as described. 40
5. In combination with a tram-car, of a laterally and vertically adjustable arm having a shipping-roller at the outer free end thereof, a lever pivotally mounted at the end of the car and provided with a laterally-movable spring-actuated roller in connection with said arm, means for sustaining the adjustment of said roller, and a switch-throw adapted to be engaged by said shipping-roller, substantially as described. 45

In testimony whereof I affix my signature in presence of two witnesses.
